UNITED STATES PATENT OFFICE.

THOMAS L. LEE, JR., OF WESTFIELD, NEW JERSEY, ASSIGNOR TO THE HALL SIGNAL COMPANY, A CORPORATION OF MAINE.

ELECTRIC-CIRCUIT-CONTROLLING APPARATUS.

1,024,587.

Specification of Letters Patent. Patented Apr. 30, 1912.

Application filed June 29, 1910, Serial No. 569,425. Renewed December 19, 1911. Serial No. 666,839.

To all whom it may concern:

Be it known that I, THOMAS L. LEE, Jr., a citizen of the United States, residing at Westfield, in the county of Union and State of New Jersey, have invented certain new and useful Improvements in Electric-Circuit-Controlling Apparatus, of which the following is a specification, reference being had therein to the accompanying drawings, 10 forming part thereof.

My invention relates broadly to contact devices for opening and closing electric circuits and is an improvement upon an invention described in my application for United 15 States Letters Patent for electric circuit controlling apparatus, filed February 12, 1910, Serial No. 543,540.

The specific embodiment of the invention illustrated in the above mentioned application 20 includes a wire gauze contact member supported at its ends and stretched between two flexible supports having an elastic tendency to separate. In this construction the wire gauze and its flexible mounting are 25 inseparably connected by rivets, so that when the comparatively perishable wire gauze wears out, both the gauze and its mounting must be renewed together.

This invention pertains to contact members included in my previous invention and 30 has for an object to render such contacts easily renewable.

Other objects and advantages of my invention will appear from the following description.

Broadly my invention comprehends a contact member arranged to be supported at two points; and a mounting therefor which has two supporting members adapted to be 40 detachably hooked to the contact member at the two supporting points.

In the specific embodiment of my invention which I have shown, the contact member is a flexible contact member under tension 45 between the supports having an elastic tendency to separate, and detachably connected to its supports; and still more specifically, the flexible contact member is wire gauze, and its ends are adapted to be detachably hooked to the supports and retained hooked by the spreading tendency of the supports.

I shall now describe my invention with reference to the accompanying drawings and shall thereafter point out my invention in 55 claims.

Figure 1 is an elevation of a complete relay in which my invention is embodied. Figs. 2, 3 and 4 are respectively a detail plan view, side elevation and end elevation 60 on enlarged scale of the flexible mounting for my contact. Figs. 5 and 6 are respectively a detail plan view and side elevation of the wire gauze contact device. Figs. 7 and 8 are respectively a detail plan and end 65 view of the end piece. Fig. 9 is a plan view of the parts of my contact assembled. Fig. 10 is an enlarged end view of the end piece showing the end of the wire gauze broken off and inserted in the end piece.

In the illustrated embodiment of my invention, the armature proper 11 is mounted upon a suitable pivot 12 in position to be attracted by the electromagnet 13. An arm or finger 14 is suitably mounted on the armature and carries an elastic or spring bow 15 bent up from any suitable flat metal stock, which carries the flexible wire gauze 16 stretched between its ends. The gauze may be of platinum, silver or other suitable conductive wire. When the armature is raised, the upper face of the gauze is pressed laterally against the contact surface of a graphite or carbon contact member 17, which may be mounted in any suitable manner. The flexibility and elasticity of the gauze and carrying bow cause the bottom to slightly bend or wrap around the bottom surface of the graphite contact, which is preferably slightly convex, whereby the gauze conforms 90 to this convex surface and effects contact therewith over a relatively great surface and at many points. These features are disclosed in my previous application above referred to.

This invention pertains to the means for attaching the wire gauze 16 to the spring support or mounting 15, which means will now be described. The wire gauze is ordinarily much shorter lived than the mounting 15, and to make the gauze renewable without removing the mounting, I provide means for removably attaching the gauze to its support so that when the gauze wears

out, it may be readily removed and a new one put in its place on the same mounting. To effect this, the mounting 15 has its supporting ends recessed or cut out for a width 5 equal to that of the gauze, thereby leaving an ear portion or lug 18 on each side of the recess, the upper end of which is bent back at an angle as shown. The gauze has its ends turned up and back like a book, 10 as shown in Figs. 5, 6 and 10, and for each end there is provided an end reinforcing or selvage member 19 which is substantially equal in length to the width of the mounting 15 and which is coiled up longitudinally 15 and adapted to fit on the end of the gauze, as shown in Fig. 10, and the ends of which project beyond the gauze at each side thereof so that they will catch under the lugs 18 of the mounting.

20 To insert a gauze contact in the mounting, the ends of the mounting are sprung together till the end pieces 19 will pass outside the ears 18 as the gauze is laid in the recesses of the mounting, and after the 25 gauze, as shown in Fig. 10, and the ends of are allowed to spring back, and the ears 18 spring over the end pieces, as shown in Fig. 9, and hold the gauze contact in the mounting, till the mounting is again sprung 30 together and the gauze released, when, if desired, the gauze may be readily lifted out and a new one inserted, thus affording extremely simple means for readily attaching and detaching the contact member.

35 It is obvious that various modifications may be made in the construction shown and above particularly described within the principle and scope of my invention.

I claim:

40 1. In an electric circuit controlling apparatus, a contact device comprising a contact member having a rough, broken or interrupted surface, a second contact device having a relatively soft or quickly wearing 45 coacting surface, and a supporting member for the first contact member consisting of two supporting arms having an elastic tendency to separate, the first contact member and the two supporting arms having hooking portions adapted to be hooked together 50 and held in hooked engagement by the separating tendency of the supporting arms.

2. In an electric circuit controlling apparatus, a contact device comprising a flexible contact member having a rough, broken or interrupted surface, a second contact device having a relatively soft or quickly wearing coacting surface, and a supporting member for the first contact member 55 consisting of two supporting arms having an elastic tendency to separate, the first contact member and the two supporting arms having hooking portions adapted to be hooked together and held in hooked con-

dition by the separating tendency of the 65 supporting arms.

3. In an electric circuit controlling apparatus, a contact device comprising a contact member having a rough, broken or interrupted surface, a second contact device having a relatively soft or quickly wearing coacting surface, and a mounting for the first contact member consisting of two supporting members having an elastic tendency to separate and having recessed supporting ends, the first contact member having hooking portions arranged to detachably hook in such recessed ends. 70 75

4. In an electric circuit controlling apparatus, a contact device comprising a flexible contact member having a rough, broken or interrupted surface, a second contact device having a relatively soft or quickly wearing coacting surface, and a mounting for the first contact member consisting of two supporting members having an elastic tendency to separate and having recessed supporting ends, the first contact member having hooking portions arranged to detachably hook in such recessed ends, the 80 first contact member being held under tension and in hooked engagement with the supporting members by the elastic tendency of the supporting members to separate. 85 90 95

5. In an electric circuit controlling apparatus, a contact device comprising a wire gauze contact member adapted to be supported at two points like a bridge, a reinforcing member for each supporting point of the contact member, and a mounting for the contact member including two supporting arms having an elastic tendency to separate, the supporting arms each having a hooking portion adapted to be detachably hooked to a reinforcing member of the contact member and to be held in hooked connection therewith by the elastic separating tendency of the supporting arms. 100 105

6. In an electric circuit controlling apparatus, a contact device comprising a contact member having laterally projecting end portions, and a mounting therefor consisting of two supporting members having recesses in their supporting ends and arranged to support the contact member in such recesses with the laterally projecting end portions extending behind the portion of the supporting members at the side of the recesses. 110 115

7. In an electric circuit controlling apparatus, a contact device comprising a contact member having laterally projecting end portions, and a mounting therefor consisting of two supporting members having an elastic tendency to separate and having recesses in their supporting ends and arranged to support the contact member in such recesses with the laterally projecting 120 125

- end portions extending behind the portion of the supporting members at the side of the recesses, the contact member being held under tension by the elastic tendency of the 5 supporting members to separate.
8. In an electric circuit controlling apparatus, a contact device comprising a contact member, a removable end piece for each end of the contact member adapted 10 when applied to project laterally thereof, and a mounting for the contact member, including two supporting members having recesses on their supporting ends and arranged to support the contact member in 15 such recesses with the laterally projecting end pieces extending behind the portion of the supporting members at the side of the recesses.
9. In an electric circuit controlling apparatus, a contact device having a flexible contact member, a removable end piece for each end of the contact member adapted when applied to project laterally thereof, and a mounting for the contact member, including two supporting members having an 20 elastic tendency to separate and having recesses on their supporting ends and arranged to support the contact member in such recesses with the laterally projecting 25 end pieces extending behind the portion of the supporting members at the side of the 30
- recesses, and the contact member being held under tension by the elastic tendency of the supporting members to separate.
10. In an electric circuit controlling apparatus, a contact device comprising a flexible conductive wire gauze contact member having hook-shaped ends, a removable end reinforcing or selvage piece for each end of the contact member and of a length exceeding the width of the contact member, whereby the end pieces when applied will project laterally of the contact member, and a mounting for the contact member including two supporting members having an 40 elastic tendency to separate and having recesses on their supporting ends and the portions at the sides of the recesses bent back at an angle and arranged to support the contact member in such recesses with the 45 end pieces extending to the side of the recesses underneath the bent back portions, the contact member being held under tension by the elastic tendency of the supporting 50 arms to separate.
- 55
- In testimony whereof I have affixed my signature in presence of two witnesses.
